[57] CLAIM

The ornamental design for a front panel of a computer main frame, as shown and described.

DESCRIPTION

FIG. 1 is a slightly reduced perspective view of a front panel of a computer main frame showing my new design;

FIG. 2 is a front elevational view thereof;

FIG. 3 is a bottom plan view thereof;

FIG. 4 is a side elevational view thereof, the opposite side being a mirror image of that shown;

FIG. 5 is a top plan view thereof; and,

FIG. 6 is a rear elevational view thereof.
